UNITED STATES PATENT OFFICE.

JAMES M. DODGE, OF PHILADELPHIA, PENNSYLVANIA, ASSIGNOR TO THE
LINK BELT ENGINEERING COMPANY, OF PHILADELPHIA, PENNSYLVANIA,
A CORPORATION OF PENNSYLVANIA.

DESIGN FOR A SPROCKET-WHEEL.

SPECIFICATION forming part of Design No. 35,390, dated December 3, 1901.

Application filed October 26, 1901. Serial No. 80,154. Term of patent 14 years.

To all whom it may concern:

Be it known that I, JAMES M. DODGE, a citizen of the United States, residing in Philadelphia, Pennsylvania, have invented and produced a certain new and original Design for a Sprocket-Wheel, of which the following is a specification.

My design for a sprocket-wheel is clearly illustrated in the accompanying drawing, which represents a side view of the said wheel.

The essential feature of the design is a wheel having the periphery notched and shaped as illustrated.

A is the body of the wheel, notched at *a* to form teeth *b* at each side of each notch.

The notches are curved, as shown, and between the notches are platforms *d*, the line of the platforms being below the line of the teeth.

I claim—

The design for a sprocket-wheel as herein described and as illustrated in the accompanying drawing.

In testimony whereof I have signed my name to this specification in the presence of 25 two subscribing witnesses.

JAMES M. DODGE.

Witnesses:

WILL A. BARR,
JOS. H. KLEIN.
